UNITED STATES PATENT OFFICE.

ORISON C. WHITNEY, OF CLEVELAND, OHIO.

CABINET-ORGAN CASE.

SPECIFICATION forming part of Letters Patent No. 251,752, dated January 3, 1882.

Application filed September 6, 1880. (No model.)

To all whom it may concern:

Be it known that I, ORISON C. WHITNEY, of Cleveland, in the county of Cuyahoga and State of Ohio, have invented certain new and useful 5 Improvements in Cabinet-Organ Cases, of which the following is a specification.

These improvements consist of a pedal-opening slide-cover, a tilting frame for fall-board, and a music-rest arranged as a music-book 10 and sheet-music receptacle, as hereinafter described and claimed.

The nature and objects of these improvements will fully appear from the subjoined description when considered in connection with 15 the accompanying drawings, in which—

Figure 1 is a front elevation. Fig. 2 is a vertical cross-section. Fig. 3 is a detached view of the tilting frame. Figs. 4 and 5 are detail views, showing grooves *a* in frame for slide- 20 cover to pedal-opening and ears on the fall-board, respectively.

A is the opening in the front of the organ, in which the pedals are operated. This opening allows dust, mice, and insects to enter. My 25 first improvement is to prevent this. I accomplish it by cutting a groove, *a*, in each side of the frame-work and providing a slide-lid, *B*, which may be raised or lowered by the foot of the operator. The lid is provided with ears *b b*, 30 which slide in the said grooves *a*. To retain the lid in the raised position a notch, *a²*, is cut in connection with the groove, into which the lower ears drop and sustain the lid. To lower the lid it is lifted slightly with the foot, which releases it from the notch. Then it is allowed to 35 slide down by its own gravity.

A second or auxiliary lid or trap, *C*, is hinged just inside of the upper edge of the pedal-opening, which extends across to the upper edge of 40 the pedals. This is raised and held up by the feet of the operator while playing, but which falls down and rests on the upper end of the pedals when the feet are removed.

D is a fall-board, which covers the keys. 45 This is attached to a tilting frame, *d*, the feet of which are pivoted to blocks *d'* on the board

d''. The top corners of said frame have short arms *e e*, to which the fall-board is attached by ears *e' e'* on its upper corners, said ears having slots cut in their lower ends, that fit onto pins 50 fixed in the arms *e e*, the slots being closed by a button, *e''*. This enables the board to be removed when desired. The two uprights of the frame are connected together by a bar, *f*, which, when the board and frame are tilted, prevents 55 one end from moving faster than the other and catching or binding. With the use of this tilting frame the fall-board readily drops into place, either forward or back, after passing the center of gravity. 60

G is a music-rest, which covers an opening in the front of the case, through which music-books and sheet-music may be put into a receptacle in the upper part of the case therefor.

The said music-rest *G* is hinged to the front 65 edge of a lid, *H*, which covers said receptacle. It can be raised to a horizontal position to open the front, and by raising it still farther the lid *H* is raised with it and uncovers said receptacle, as seen in dotted lines, Fig. 2. 70

Having described my invention, I claim—

1. The lid *B*, provided with the ears *b b*, arranged and adapted to slide in the grooves *a a*, having notches *a²* in the frame-work of the case, to afford a covering for the pedal-opening, as 75 set forth.

2. The tilting frame consisting of the two uprights *d d*, connected by bar *f*, and pivoted to blocks *d' d'* on the board *d''*, and provided with the short arms *e e*, to which the fall-board 80 *D* is attached by the ears *e' e'*, having buttons *e''*, all arranged to operate as and for the purpose specified.

3. The music-rest *G*, hinged to the front edge of the lid *H*, the said rest *G* forming a covering to the front opening, and the lid *H* a cover on the top of the music-receptacle, as shown and described. 85

O. C. WHITNEY.
